Primary Examiner — Cathron C Brooks*Assistant Examiner* — W. A. Teddy Falloway(74) *Attorney, Agent, or Firm* — Dinsmore & Shohl LLP(57) **CLAIM**

The ornamental design for a multi-compartment pouch, as shown and described.

DESCRIPTION

FIG. 1 is a perspective view of the top and front of a multi-compartment pouch;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top elevational view thereof; and,

FIG. 7 is a bottom elevational view thereof.

It should be appreciated that the broken lines illustrate environmental structure and portions of the multi-compartment pouch that form no part of the claimed design.
